CONVEYER

Nicholas Pelosi, Newark, N. J., assignor to American Can Company, New York, N. Y., a corporation of New Jersey

Application July 18, 1940, Serial No. 346,205

3 Claims. (Cl. 198—160)

The present invention relates to can or container conveyers and the like and has particular reference to a conveyer which has propelling fingers which makes point contact with a can to be propelled so that the can will be prevented from being crushed against the conveyer while traveling along curved paths of travel.

In propelling rectangular and the like shape cans of light weight material such as fibre cans, the usual flat faced conveyer fingers generally found in can conveyers prevent movement of the can relative to the fingers when traveling along curved paths of travel and hence the corners of the cans sometimes bind against the fingers and this results in a jamming of the can against the conveyer. This usually crushes the can and causes considerable trouble in the conveyer.

The instant invention contemplates overcoming this difficulty by providing pointed contact elements on the conveyer fingers which permit the can to rotate or pivot relative to the fingers while being conveyed along a curved path of travel and thereby prevent crushing of the can and jamming of the conveyer.

An object therefore of the invention is the provision of a can conveyer having can propelling fingers thereon at spaced intervals along its length wherein the fingers are formed with pointed contact elements which engage the can at predetermined points and thus permit movement of the can relative to the propelling fingers when the can is being conveyed along a curved path of travel and thereby prevent crushing or other distortion of the can during conveyance.

Another object is the provision in such a can conveyer, of devices which hold the conveyer firm while moving along its path of travel and prevent whipping of the conveyer with deleterious effects upon the cans carried thereon.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a can conveyer embodying the instant invention, with parts broken away;

Fig. 2 is an enlarged transverse sectional view taken substantially along the line 2—2 in Fig. 1, the view being turned through an angle of ninety degrees; and

Fig. 3 is an enlarged view of the upper end of the conveyer shown in Fig. 1, the view illustrating how a can body travels around a curved path of travel.

As a preferred embodiment of the instant invention the drawings illustrate a continuously moving vertical elevator for carrying light

weight rectangular can bodies A from one elevation to a higher elevation and thence around a curved path of travel.

Such an elevator includes a vertically disposed endless chain conveyer 11 (Figs. 1, 2 and 3) which takes over a lower sprocket 12 and an upper sprocket 13. The lower sprocket is mounted on a driving shaft 15 which is journaled in suitable bearings formed in a machine base housing 16. The shaft may be rotated in any suitable manner. The direction of rotation of the shaft is such that the conveyer chain 11 travels upwardly along the front of the machine (at the left as viewed in Fig. 1), over the sprocket 13 and thence down toward the sprocket 12.

The upper sprocket 13 is mounted on an idler shaft 18 which is journaled in bearings 19 formed in a vertical frame 21. The frame is formed on a cover plate 22 which is secured to the top of the base housing 16.

At spaced intervals, the chain conveyer 11 is provided with can carrying or propelling members or flights 25. These members are formed with link portions 26 which are connected into the chain 11 and which constitute links of the chain. The members extend outwardly from the chain and branch into two angularly disposed arms 21. These arms carry pointed can engaging elements or lugs 28 which are disposed adjacent the outer ends of the arms.

In order to prevent whipping or vibration of the chain conveyer 11 as it travels upwardly along the front of the frame 21, the link portions 26 of the members 25 carry cam rollers 31 which are mounted on pins 32. The pins are carried in and extend transversely of the link portions 26, the rollers being carried on the outer ends of the pins. These rollers operate in vertical cam tracks 33 formed on the front face of the frame 21 and which are adjacent the path of travel of the chain conveyer.

Hence as a member 25 on the chain conveyer 11 passes under the lower sprocket 12 and starts upwardly along the front of the machine, its rollers 31 immediately engage in and travel along the tracks 33. This guides the members while they travel upwardly and it is this guiding action of the members 25 that prevents whipping and undue vibration of the chain conveyer.

The can bodies A to be carried in the elevator enter the machine in a horizontal position passing along a runway or table 36 which is disposed near the bottom of the elevator. The machine end of the table is secured to a bracket 37 which is bolted to the housing cover plate 22. The table extends into the path of travel of the conveyer members 25 and is provided with a clearance opening therein to permit the passage of the members as they travel upwardly with the chain.

The can bodies may be advanced along the

table 36 in any suitable manner, preferably by means which permit them to engage and push each other into the path of travel of the conveyer members. Hence as a conveyer member 25 travels upwardly along the front of the elevator, the two pointed elements 28 of the members engage under the innermost can body A on the table and carry it upwardly with the moving conveyer.

During this upward travel, the can bodies are retained in position on the carrying members 25 by spaced and parallel guide rails 41 which are disposed adjacent the path of travel of the bodies. There are preferably six of these guide rails, located two adjacent the inner surface of the bodies, two adjacent the outer surface, and one at each end of the bodies as best shown in Fig. 2. These guide rails are secured in a pair of spaced brackets 42 which are bolted to pads 43 formed on the machine frame 21.

Adjacent the body entering table 36 the two outer guide rails 41 are cut short to permit the entering can bodies to pass under them as the bodies move into position adjacent the conveyer. The remaining guide rails extend down alongside of the table and properly locate the incoming body prior to its being picked up by a conveyer member.

At the top of the elevator the guide rails curve around the sprocket 13 and thence extend downwardly at an angle to a suitable place of deposit for the can bodies. These angularly disposed portions of the guide rails are secured to a bracket 45 which is bolted to pads 46 formed on the frame 21.

When a can body A is pushed around this curved portion of the guide rails, the pointed elements 28 of the members 25 permit the body to rotate slightly relative to the member as best shown in Fig. 3. This prevents the adjacent inner corner of the body from coming into contact with the member and also prevents a pressure from being exerted at the corner of the body thus obviating any forcing of the parts out of square or any jamming against the guide rails. With the point contact as provided by the member elements 28, the body is pushed around the curved section of the guide rails without distortion whereupon it slides down the inclined section to any suitable place of deposit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a can elevator, the combination of a continuously movable endless conveyer having a straight vertical section and a connected curved section disposed above said vertical section, can retaining guide members also including a straight vertical section and a curved section respectively extending along and around said straight and curved conveyer sections and engageable with opposite sides of a can propelled by said conveyer, can carrying members disposed in spaced relation on said conveyer respectively for propelling rectangular cans in spaced relation along a predetermined connected straight and curved path

of travel while the cans are retained between said straight and curved sections of the guide members, and rigid conical can engaging elements carried on and projecting laterally from said members and adapted to respectively engage against a can in point contact so that the cans may tilt on their longitudinal axes relative to said can engaging elements while being continuously propelled in spaced relation along the straight and curved conveyer sections without being crushed against said guide members.

2. In a can elevator, the combination of a continuously movable endless conveyer having a straight vertical section and a connected curved section disposed above said vertical section, can retaining guide members also including a straight vertical section and a curved section respectively extending along and around said straight and curved conveyer sections and engageable with opposite sides of a can propelled by said conveyer, and can carrying members secured to said conveyer at spaced intervals along its length, each member having a pair of outwardly extending arms and each arm having a rigid conical can engaging element projecting laterally therefrom for making point contact with rectangular cans fed into said conveyer for continuously propelling said cans in spaced relation along the predetermined connected straight and curved paths of travel defined by said conveyer and guide members while the cans are retained between said straight and curved sections of the guide members, the point contact with said cans allowing pivotal movement of the cans relative to the carrying members so that the cans may tilt on their longitudinal axes relative to and while being maintained in spaced relation by said can engaging elements, whereby said cans may be propelled along said straight and curved paths of travel without being crushed by the carrying members against said guide members.

3. In a can elevator, the combination of a conveyer having a straight vertical section and a connected curved section, can retaining guide members also including a straight vertical section and a curved section respectively extending along and around said straight and curved conveyer sections and engageable with opposite sides of a can propelled by said conveyer, can carrying members secured to said conveyer at spaced intervals along its length, can propelling arms formed on each of said members for moving the cans while the same are retained between said straight and curved sections of the guide members, rigid can engaging elements respectively formed on said arms and adapted to engage against a can in point contact so that the cans may tilt on their longitudinal axes relative to said can engaging elements and readily propelled along the predetermined straight and curved paths of travel defined by said conveyer and guide sections while the cans are retained between said straight and curved sections of the guide members to insure against crushing the cans by said conveyer carrying members against said can retaining guide members, a cam track disposed adjacent the vertical path of travel of said conveyer, and cam rollers carried by said members and adapted to operate in said cam track to guide said conveyer and to prevent whipping thereof while moving along said vertical path of travel.

NICHOLAS PELOSI.
